UNITED STATES PATENT OFFICE

JOHN S. KNEE, OF GRAND RAPIDS, MICHIGAN

DAMPER

Application filed March 14, 1930. Serial No. 435,780.

The present invention relates to dampers and more particularly to dampers adapted for use with furnaces and stoves.

The object of the invention is to provide a damper having two draft doors operated simultaneously and in the same degree by a single chain or cable, thereby increasing the maximum amount of draft supplied and distributing it more evenly in the pipe or flue; and further to provide means whereby the damper may be remotely controlled.

These objects are attained by, and the invention finds preferable embodiment in the structure or device hereinafter particularly described in the body of this specification and illustrated by the accompanying drawings, in which:

Figure 1 is a top plan view of the damper, certain parts being shown in section taken 20 on line 1—1 of Figure 2;

Figure 2 is an elevational view of the same, a portion of one end being broken away to show the interior, and showing in dotted lines fragments of the draft doors 25 in raised or open position; and

Figure 3 is a fragmentary sectional view taken on line 3—3 of Figure 2.

The device generally comprises a casing having draft doors at either side thereof, 30 a partition interjacent the draft doors, and end openings provided with annular flanges adapted to connect with sections of horizontally disposed furnace or stove pipe.

Referring to the drawings, the central 35 part of the casing, generally designated 1, has a rectangular horizontal bottom portion 2, square vertical end portions 3 and 4 with circular openings therethrough, and a rectangular horizontal top portion 5, to each 40 end of which is secured by means of rivets 6, a pair of plates 7 whose outer ends are curled to form pintle bearings 8 for the suspension of the oppositely disposed draft doors 9.

The side parts of the casing are identical 45 in construction, each having a rectangular horizontal bottom portion 10 and vertically disposed triangular end portions 11 whose outer edges slope from the side edge of the 50 top portion 5 to the outer edge of the bottom

portion 10. The inner edges of these portions 10 and 11 are bent to form right angularly disposed U-shaped grooves 12 into which fit the flanges 13 of the central part of the casing, in tongue and groove relationship. 55

It will be seen that the casing may be constructed of one integral sheet of metal, but the construction herein shown and described is stronger and less subject to distortion. 60

The circular openings in the end portions 3 and 4 of the casing 1 are provided with annular pipe-mounting members 14, which have outwardly flanged portions 15 adapted to abut against the outside of the end walls 3, 65 4 adjacent the circular openings, and are secured as by rivets 16 to auxiliary annular members 17 telescoping therewith and likewise having outwardly flanged portions 18 adapted to abut against the inside of the end 70 walls 3, 4 adjacent the circular openings.

The draft doors 9 have their upper edges curled to form pintle bearings 19 for hingedly securing the draft doors to the opposite outer edges of the top portion 5 of the casing 75 by the pintles 20, which pass through the bearings 19 on the doors and the bearings 8 on the top portion. The draft doors are further provided with integral inwardly extending flanges 21 which are adapted to fit outside the 80 end portions 11 of the casing, to provide a more perfect closure for the open sides of the casing when the draft doors are in lowered or closed position.

Rigid bars 22 are secured as by rivets 23 85 to the draft doors intermediate the sides thereof, and have twisted portions 24 and upwardly-outwardly projecting tongue portions 25 which have at their upper ends apertures 26. Chains 27 whose outer ends are secured in the apertures 26 have their inner ends connected to a link 28 situated directly above the center of the device. In cases where the damper is installed too near the ceiling or the chains are otherwise hindered from passing upwardly, they may be secured in the apertures 29 in the brackets 30, which are secured to the draft doors near the lower edges thereof by means of rivets 31. In such cases the chains may pass through pulleys sus- 95 100

pended from the ceiling or other suitable mooring and connected together at a point below the center of the casing.

Common means may be employed for exerting a pull upwardly (or downwardly in the exceptional cases above indicated) at the central point of connection of the chains, thus opening the draft doors as indicated in the dotted lines of Figure 2. These means may also include a weight or its equivalent for counter balancing the doors in adjusted positions.

Midway between the open sides of the casing and in longitudinal alignment with the circular end openings, is a vertically disposed plate 32 having horizontally projecting flanges 33 at its upper and lower edges, which are secured as by rivets 34 to the top and bottom of the casing, thus dividing the casing into two sections so that in the event outside air currents cause a difference in pressure at the two draft door openings, the draft entering one door cannot pass through the casing and out the other door, but is properly carried with the products of combustion into the furnace or stove pipe or flue.

The invention being intended to be pointed out in the claim, is not to be limited to or by details of construction of the particular embodiment thereof illustrated by the drawings or hereinbefore described.

I claim:

In a damper; a casing having a top, a bottom, open sides, and end portions provided with openings therethrough adapted to connect with sections of stove pipe, draft doors at the open sides of said casing, and a vertical plate in longitudinal alignment with and between said openings in said end portions.

In testimony whereof I have hereunto set my hand at Grand Rapids, Michigan, this 22nd day of February, 1930.

JOHN S. KNEE.
